REEL TRAVERSE

George G. Tucker, Jr., Berwyn, Ill., assignor to
 Hubbard Spool Company, Chicago, Ill., a corporation of Illinois

Application December 8, 1950, Serial No. 199,750

3 Claims. (Cl. 242—124)

1

The present invention relates to a reinforced traverse or barrel construction for reel or spool assemblies.

A common practice among users of wire holding spools is that of manufacturing their own end flanges for spool assemblies to be used in wire winding machines, the flanges being manufactured specifically for the particular wire winding machines in the plant of the user. The reel traverse portion of the spool assembly is purchased from a supplier, the selection of a particular type of traverse being dependent upon the type of wire which would be wound upon the spool. Such users then assemble the separately manufactured reel traverses with the end flanges particularly designed for their machines.

The objections to the use of prefabricated reel traverses are primarily concerned with their cost. Conventionally, such reel traverses are fabricated from seamless steel tubes which are rather expensive. A further objection to the use of this type of reel traverse resides in their relative bulkiness, as such traverses require considerable space in shipping, and in storage prior to their assembly with the end flanges to complete the spool assembly.

In the present invention, I have provided a reel traverse composed of segmental sections which can be easily assembled into a circular reel traverse and assembled with the end flanges into a completed spool. The individual segmental sections may be conveniently manufactured from ordinary sheet metal and rapidly assembled into a substantially rigid reel traverse. In several of the embodiments of the invention, means are provided on the segmental sections to facilitate locking the sections in place, and thereby avoid slippage between individual sections when the sections are in assembled position.

One of the objects of the present invention is to provide a traverse for reel construction.

Another object of the present invention is to provide a new type of traverse for a reel which can be manufactured simply and economically from ordinary sheet metal stock.

Another object of the present invention is to provide a traverse construction with reinforcing ribs extending axially of the traverse so that the reel may accommodate substantially greater loads of wire or cable without buckling or deformation.

In the present invention, I have provided a traverse section for a reel assembly which includes a plurality of segmental sections having

2

longitudinally extending flange portions in abutting contact to form a circular traverse with axially extending reinforcing ribs. One of the features of the invention resides in the simplicity and economy of manufacture of such traverse members, the cost of a steel traverse member produced according to the present invention being even less than a wood traverse of the same outer diameter.

10 A further description of the present invention will be made in connection with the attached sheets of drawings, in which:

Figure 1 is a view in elevation, partially in cross-section of a spool assembly, showing the reel traverse of the present invention in assembled relation with end flanges;

Figure 2 is a cross-sectional end view of the structure shown in Figure 1;

Figure 3 is a plan view of a blank used in forming the segmental portions in making up the traverse;

Figure 4 is an end view of the blank of Figure 3 after the same has been curved and bent over into a segmental section;

Figure 5 is a view in elevation of a segmental section representing a modified form of the present invention;

Figure 6 is a fragmentary view showing how two of the segmental sections illustrated in Figure 5 are joined together in the completed reel traverse;

Figure 7 is a plan view of a blank used in forming another modified form of the present invention;

Figure 8 is a view in elevation of the blank in Figure 7 after the same is curved into an arcuate section; and

Figure 9 is a fragmentary view showing how two abutting sections of the type shown in Figures 7 and 8 are assembled in the completed reel traverse.

As shown on the drawings:

As best illustrated in Figures 1 and 2, the reel traverse or barrel of the present invention consists of a plurality of segmental sections 10, there being four identical sections 10 in the form of the invention illustrated in Figures 1 and 2, although it will be appreciated that the reel traverse may be composed of more or less than the four sections illustrated.

Each of the sections 10 has portions 11 and 12 adjacent its opposed marginal edges bent inwardly so that these portions extend along the radius of curvature of the completed reel traverse. In this manner, when the individual seg-

mental portions 10 are placed together in assembled relationship, as illustrated in Figure 2, the longitudinal end portions 11 and 12 lie flat against the corresponding longitudinal end portions of the segmental sections 10 immediately adjoining the same.

The opposite ends of each of the sections 10 are inwardly turned to form annular flange portions 13. Each of the flange portions 13 is suitably apertured as indicated at 14 to receive 10 spaced bolts 15 therethrough.

In assembling the individual sections 10 into the completed reel assembly, the annular flange portions 13 are wedged within an annular recess 17 formed in each of a pair of identical end flanges 18 and 19. The sections 10 are aligned in the annular recess 17 to form a circular traverse, whereupon the opposing end flange 19 is pressed over the opposite ends of the reel traverse. While not shown in the drawing, it will be understood that the end flange 19, similarly to the end flange 18, has a radial recess for retaining the annular flange 13 therein.

After assembly of the reel traverse and to the end flanges 18 and 19, the securing bolts 15 are passed through the flanges 18 and 19 as well as the apertures 14 in the reel traverse section. Securing nuts 20 force the end flanges 18 and 19 into tight engagement with the reel traverse portion to prevent relative movement between 30 the individual sections 10 due to centrifugal force during the rotation of the spool assembly.

The method of manufacturing the individual sections 10 shown in Figure 2 can be best described in connection with Figures 3 and 4. As shown on these two figures, the sections 10 may be fabricated from a substantially rectangular blank 21 of suitable sheet metal material which for example may be sixteen gauge sheet steel. The corners of the blanks 21 are cut away as indicated at 22 to facilitate bending of the edges of the blank 21. At the time that the individual blanks 21 are stamped from a piece of sheet metal, the apertures 14 are also punched out with suitable dies. In the embodiment of the invention illustrated in Figures 1-4, each of the blanks 21 is provided with three spaced apertures 14 on each edge of the blank. As shown in Figure 2, a maximum of two of the apertures will be used to retain the securing bolts 15. However, it is desirable to provide more apertures than required in any one section, so that each of the blanks 21 will be identical, and no inconvenience will result in having to select different segmental sections to provide proper location of the securing bolts 15.

After stamping of the blank 21 in the manner shown in Figure 3, the edge portions 13 are turned inwardly to form the annular flange portion engaging the flange members 18 and 19. At the same time, the blank 21 is given an arcuate shape, as illustrated in Figure 4, and the opposite edge portions 11 and 12 are also turned radially inwardly to form the longitudinally extending ribs illustrated in Figure 2. As previously described, the marginal end portions 11 and 12 are bent such that they lie along a radius of curvature of the completed circular reel traverse, so that the edge portions 11 and 12 of adjoining segments 10 lie flat against each other in abutting contact.

A modified form of the segmental section is illustrated in Figures 5 and 6. The blank used in fabricating this modified form may be the same as that illustrated in Figure 3. In addition, however, the portions 11 and 12 adjacent the

marginal edges are provided with struck out tabs 25 at spaced points therealong. Striking out the integral tabs 25 from the sheet metal form results in the production of apertures 26 in both the marginal edge portions 11 and 12.

The tabs 25 are struck out at different points along the marginal edge portion 12 then at the opposed marginal edge portion 11. Thus, when two of the sections 10 are placed in abutting contact, the tabs 25 formed in the edge portion 11 extend through the apertures 26 formed in the marginal edge portion 12 of the adjoining segment 10. In the same manner, the tabs 25 of the marginal edge portion 12 extend through the apertures 26 of the adjoining segment 10. An efficient interlock is thereby provided between the abutting tabs 25 to prevent relative movement longitudinally between the abutting segments 10.

Still another modified form of the present invention is illustrated in Figures 7-9, inclusive. In the modification there illustrated, a blank 30 is provided with serrated edge portions providing teeth or tabs 31 adjacent one marginal edge thereof, and similar tabs 32 at the opposed edge portion. As best illustrated in Figure 7, the tabs 32 and the tabs 31 are in staggered relation with respect to each other, each of the tabs 31 being longitudinally aligned with the recessed portion between the individual tabs 32.

In shaping the blank 30 into the arcuate shape desired in the finished segmental sections, the blank 30 is also stamped to offset the tabs 31 and 32 from the remainder of the stock. This offsetting is perhaps best illustrated in Figure 9, which shows two similar segmental sections 40 interlocked adjacent their marginal edges by the interengagement of the tabs 31 and 32 at their respective marginal edge portions into a hinge-type engagement.

The embodiment of the invention illustrated in Figures 7-9, inclusive is a particularly preferred one because it obviates the necessity of providing the annular recesses in the flange assemblies, corresponding to recess 17 in Figure 1. As the individual sections 40 are assembled, the interengaging tabs 31 and 32 lock the segmental sections together to form a self-sustaining rigid structure. The spool assembly can then be conveniently assembled by merely placing the end flanges 18 and 19 over the self-sustaining reel traverse and inserting the locking bolts 15 through the appropriate apertures in the end flanges 18 and 19 as well as the completed reel traverse.

From the foregoing it will be apparent that I have herein provided a novel and economical type of reel traverse which may be manufactured from simple metal stampings. The reel traverses of the present invention are sturdy, and capable of resisting substantial axial as well as radial thrust.

It will be appreciated that various modifications may be effected without departing from the scope of the novel concepts of the present invention.

I claim as my invention:

1. A reel traverse comprising a plurality of segmental sections, each of said sections having portions adjacent the marginal edge thereof formed with off-set integral tabs extending therefrom and having spaced substantially parallel opposed sides, said tabs being arranged to engage similar portions of a similar section to form a circular traverse with the engaging portions resisting axial displacement of one of said segmental sections with respect to others of said

segmental sections, each of said sections also having opposed pairs of marginal edges bent inwardly thereof to form annular flanges at opposite ends of said traverse.

2. A reel traverse comprising a plurality of segmental sections, each of said sections being arcuately shaped and having off-set tabs provided with substantially spaced parallel sides and formed at portions adjacent opposed marginal edges thereof, the tabs at one edge being staggered with respect to the tabs at the opposed edge of the same section such that upon assembly of said section into a circular traverse, the tabs on adjoining sections interlock to form a self-sustaining circular reel traverse, said sections each having opposed marginal portions bent inwardly to form upon assembly of said traverse, opposed annular flange portions at opposite ends of said traverse.

3. A reel traverse comprising a plurality of segmental sections each having a pair of opposed ends, each of said sections being arcuately shaped and having inwardly bent opposed marginal side portions, each of said sections having their ends off-set inwardly and notched to provide a plurality of spaced off-set tabs, said tabs at one end of each of said sections being staggered with respect to the tabs at the other end thereof, whereby upon assembly the tabs on adjoining sections interlock within said notches with the 30

inner edge of each of said notches in juxtaposition with respect to the inner ends of said off-set tabs on the adjoining sections to form a self-sustained circular reel traverse with a substantially continuous external curvilinear surface, and said inwardly bent marginal side edges defining substantially continuous annular flanges at each end thereof.

GEORGE G. TUCKER, JR.
